UNITED STATES PATENT OFFICE.

CHARLES FREDERICK ROTHWELL, OF COLUMBUS, MONTANA.

BASKET.

1,387,185.

Specification of Letters Patent.

Patented Aug. 9, 1921.

Application filed October 30, 1920. Serial No. 420,650.

To all whom it may concern:

Be it known that I, CHARLES F. ROTHWELL, a citizen of the United States, and a resident of Columbus, county of Stillwater, 5 and State of Montana, have invented a new and Improved Basket, of which the following is a full, clear, and exact description.

This invention relates to improvements in baskets, particularly to that class of baskets 10 which are commonly employed by undertakers for transferring a body from one point to another, and are known in the trade as "pick up" baskets.

An object of my invention is to provide 15 improved means whereby the manual lifting of a corpse from the pick up basket on to the embalming table is eliminated, and the operation is thus made more sanitary, and the danger of spreading disease is lessened.

20 A further object is to provide a pick up basket which will be simple and practical in construction, and strong, durable, and efficient in use.

With these and other objects in view, the 25 invention consists in certain novel features of construction, and combinations and arrangements of parts as will be more fully hereinafter described, and pointed out in the appended claims.

30 In the accompanying drawings:

Figure 1 is a bottom plan view of my improved basket.

Fig. 2 is an enlarged view in transverse section on the line 2—2 of Fig. 1 showing 35 the doors in closed position.

Fig. 3 is a view similar to Fig. 2 showing the doors in open position.

Fig. 4 is a still further enlarged fragmentary bottom plan view of one end of 40 the basket with parts broken away to show the details of the locking mechanism.

Fig. 5 is a fragmentary view in longitudinal section on the line 5—5 of Fig. 4.

The basket comprises an oval base frame 45 1 upon which is built side walls 2 of reeds or some similar material. The removable cover 3 is also made of reeds as is customary with this form of basket. Suitable flexible handles 4 are attached to the ends of the 50 oval base frame 1.

My invention resides particularly in the provision of an improved bottom or floor for the basket, and a locking mechanism associated therewith.

55 A pair of doors 5 shaped in conformity

with the oval frame are hinged to the sides of the frame and open downwardly and outwardly. The hinges 6 which are employed to hinge the doors 5 to the frame 1, are made integral with bracket portions 7 60 screwed to the top side of the frame 1 and strengthening the hinged connection of the doors and frame.

Truss rods 8 and turn buckles 9 to operate the rods are secured to the under faces of 65 the doors 5 and serve to strengthen the same.

The basket is supported on casters 10 mounted in suitable brackets 11 on the under face of the frame 1. At each end the oval frame 1 is recessed to receive a plate 12, the 70 outer face of which lies flush with the outer face of the frame. Under the plates the frame is recessed as shown at 13 to accommodate the heads 14 of screws 15 positioned through centrally located openings in the 75 plates, and projecting from the ends of the frame 1. It will be understood that while the plates serve to retain the head 14 of the screws 15 in the recesses 13, they in no way hamper the turning movement of the 80 screws.

Any suitable finger receiving devices such as 16 are provided on the outer end of the screws to facilitate manual turning of the same.

The plates 12, the ends of the frame 1, and the doors 5 are formed with aligned bolt receiving openings 17 as shown clearly in Fig. 4.

Upon each of the screws 15 is mounted a 90 bolt carrying yoke 18 having a centrally disposed screw threaded opening engaging the threads of the screws 15 and carrying a pair of bolts 19 adapted to be moved into the recesses 17 by a turning movement of 95 the screws 15, and to lock the doors 5 against opening as will be readily understood.

I do not desire to be limited to any particular means for operating the screws as it is apparent that various operating devices 100 might be employed without departing from the spirit of my invention.

The operation is as follows: When a body is "picked up" to be transferred from a house to the undertaking parlors, the doors 105 are of course kept in locked position by the bolts, and the body is introduced into the basket from the top. When it is desirable to transfer the body from the basket to the dressing or embalming table in the under- 110

taking establishment, it is merely necessary to place the basket on the table and operate the screws 15 to move the yokes outwardly and retract the bolts. The basket is then 5 lifted upwardly, the weight of the body opening the doors 5 as the basket is lifted. The door construction obviates any unnecessary handling of the corpse which remains on the table as the basket is removed.

10 While I have illustrated one of the preferred embodiments of my invention, it is apparent that various slight changes and alterations might be made in the general form of the parts described without departing 15 from my invention, and hence I do not wish to limit myself to the precise details set forth but shall consider myself at liberty to make such slight changes and alterations as fairly fall within the spirit and scope of 20 the appended claims.

I claim:

1. As a new article of manufacture, an enclosed body carrying basket including a base frame, a pair of doors hinged to the sides 25 of the base frame and swingable downwardly and outwardly, and devices movable

through the ends of the frame to lock the doors in closed position.

2. In a basket of the character described, a base frame, a pair of doors hinged to the 30 base frame screws secured to the ends of the frame and turnable therein, yokes having screw threaded openings fitting the screws, said frame and doors having alined openings therein, bolts carried by the yokes, 35 and means whereby turning movement of the screws in one direction moves the bolts into locking position in the openings.

3. In a basket of the character described, an oval base frame, a pair of doors hingedly 40 connected to the base frame, said base frame and doors having alined bolt receiving openings in their ends, plates, screws held against longitudinal movement by the plates but free to turn, devices on the ends of the 45 screws for turning the same, yokes movable on the screws, bolts carried by the yokes, and movable in said alined recesses whereby turning movement of the screws operate the bolts.

CHARLES FREDERICK ROTHWELL.
